(57) **CLAIM**

The ornamental design for a hanging lamp, as shown and described.

DESCRIPTION

FIG. 1 is a perspective view of a hanging lamp according to one embodiment of our new design;

FIG. 2 is a front elevational view of the hanging lamp shown in FIG. 1;

FIG. 3 is a back elevational view of the hanging lamp shown in FIG. 1;

FIG. 4 is a left side elevational view of the hanging lamp shown in FIG. 1;

FIG. 5 is a right side elevational view of the hanging lamp shown in FIG. 1;

FIG. 6 is a top view of the hanging lamp shown in FIG. 1;

FIG. 7 is a bottom view of the hanging lamp shown in FIG. 1;

FIG. 8 is a perspective view of a hanging lamp according to a second embodiment of our new design;

FIG. 9 is a front elevational view of the hanging lamp shown in FIG. 8;

FIG. 10 is a back elevational view of the hanging lamp shown in FIG. 8;

FIG. 11 is a left side elevational view of the hanging lamp shown in FIG. 8;

FIG. 12 is a right side elevational view of the hanging lamp shown in FIG. 8;

FIG. 13 is a top view of the hanging lamp shown in FIG. 8; and,

FIG. 14 is a bottom view of the hanging lamp shown in FIG. 8.

The broken lines are for illustrative purposes only and form no part of the claimed design.
